UNITED STATES PATENT OFFICE.

PAUL BATEMAN, OF WEBSTER GROVES, MISSOURI, ASSIGNOR TO AMERICAN CAR AND FOUNDRY COMPANY, OF ST. LOUIS, MISSOURI, A CORPORATION OF NEW JERSEY.

CAR-ROOF WITH INTERLOCKING FRAME.

1,276,313.

Specification of Letters Patent. Patented Aug. 20, 1918.

Application filed July 23, 1914. Serial No. 853,708.

To all whom it may concern:

Be it known that I, PAUL BATEMAN, residing at Webster Groves, Missouri, and being a citizen of the United States, have invented certain new and useful Improvements in Car-Roofs with Interlocking Frames, of which the following is a full, clear, and exact description, such as will enable others skilled in the art to which it applies to make and use the same, reference being had to the accompanying drawings, which illustrate the preferred form of the invention; though it is to be understood that the invention is not limited to the exact details of construction shown and described, as it is obvious that various modifications thereof will occur to persons skilled in the art.

In said drawings:

20 Figure 1 is a sectional view taken transversely through the carline showing part of a ridge pole or purlin interlocking therewith.

25 Fig. 2 is a side elevation of part of a carline, the penetrating and interlocking ridge pole or purlin being shown in section.

Fig. 3 is a side elevation of the notched part of the purlin; and

30 Fig. 4 is a side elevation of the apertured part of the carline.

Railroads in general require in their rolling stock equipments, cars which possess maximum inside dimensions. All cars are limited in height by the roofs of the tunnels 35 through which they pass and the floors of bridges and viaducts under which they run, and freight cars are particularly limited in this respect, as they are interchanged and run over many roads. They must, therefore, conform to the extreme limitations of all of the roads.

Usually the carlines of a car are positioned either above or below the ridge pole and purlins, or the latter are inset in carlines, which to have the proper strength have a considerable depth, in each instance materially decreasing the available inside height of the car.

It is one of the purposes of my invention 50 to construct the ridge pole, purlins and carlines of a material, such as steel, as will permit these members to have minimum dimensions commensurate with the requisite strength.

55 Another object is to cause the ridge pole

and purlins to be substantially confined within the vertical limits of a carline of small depth, and a further aim is to interlock the intersecting members so that they may be framed into each other without being directly riveted one to the other.

There has also been provided means that complete the interlocking relation of the parts and which permit the roof frame to be assembled with very little riveting.

Referring to the drawings, 1 represents a carline, illustrated as an I-beam, provided with an opening 2 substantially conforming to the contour of a purlin 3, which may be a standard T. The upper portion 2^a of opening 2 in carline 1 is of greater area than is necessary to admit the flanges of the T-bar forming the purlin 3, and the lower portion 2^b of said opening, best shown in Fig. 4, is in the form of a relatively narrow slot.

At points intersecting with the carlines, each purlin 3 is provided with a notch 4 in the depending or vertically disposed leg 5 thereof.

The purlin 3 is threaded through opening 2 in the carline 1, and, in the assembling process, said purlin, during the greater part of its insertion through the carline, practically fills the opening 2 in the latter except for the space below the horizontal leg of 85 said purlin and above the slot or lower part 2^b of opening 2.

But, when notch 4 in purlin 3 becomes centered with respect to carline 2, purlin 3 drops to a lower level, the horizontal edge 90 5^a of web 5 of purlin 3, which is within the notch 4, is in proximity to the metal at 2^c, which forms the lower boundary of slot 2^b of opening 2 in carline 1.

With the parts so arranged, the under inclined sides of the horizontal leg of purlin 3 may bear against the inclined portions of the outline of opening 2, and shoulders 5^b of notch 4 lap the bottom flange of the I-beam constituting the carline 1.

Secured to web 5 or purlin 3, as by a rivet 6, is a retaining clip 7, comprising a back plate 8, flanges 9 and a rib-strengthened horizontally disposed foot 10, the latter adapted to project underneath the bottom flange of 105 carline 1.

The horizontal leg of the purlin 3 is adapted to support a roof sheet 11, which is crimped and has a vertical portion arranged to lie against the web of carline 1 and the 110

under inclined surface of the top flange thereof. The upper surface of the top flange of said carline is adapted to support a washer 12, through which extends a bolt 13 which may serve for attaching a running board or other device to the roof frame. Said washer is inclosed and may be positioned by a cap 14, which is preferably continuous and also serves to inclose the edges 10 of adjacent roof sheets.

When the parts are entirely assembled, edge 5^a of the web of the T-shaped purlin 3 and foot 10 of retaining clip 7 prevent any relative vertical movement between the carline 1 and purlin 3. Transverse movement between these members is precluded by shoulders 5^b of notch 4, which, as stated, lap the bottom flange of carline 1, and by the vertical walls formed by the opening 2 20 in said carline.

It, therefore, is seen that my roof structure is easily assembled or taken apart, and that it requires little shop treatment, is securely held against displacement and provides a 25 construction which possesses space-saving qualities, reliability and is of relatively low cost.

What I claim is:—

1. In a roof, a flanged carline provided 30 with a T-shaped perforation, a notched purlin of T-shape section adapted to pass through said perforation, the horizontal leg of the perforation being wider than the horizontal leg of said purlin, said purlin by reason of its notch and the horizontal leg of said 35 perforation being adapted to assume an interlocking relation with said carline, and a retaining clip secured to said purlin and opposing movement of said carline for maintaining the lower edges of the carline and purlin substantially coincident.

2. In a roof, an I-shaped carline provided 40 with a T-shaped perforation, a notched purlin of T-shaped section projecting through said perforation, the horizontal leg of the latter being wider than its own vertical leg and the horizontal leg of said purlin, said 45

purlin by reason of its notch and the horizontal leg of the perforation being adapted to assume an interlocking relation with said carline, and a retaining clip secured to said purlin and projecting beneath said carline to maintain a relatively flexible connection between the purlin and the carline. 50

3. In a car roof, carlines composed of I-beams having T-shaped openings in the webs thereof, in combination with T-shaped purlins passing through the openings in said carlines, the webs of said purlins being notched to inclose the lower flanges of said 60 carlines, a roofing sheet having a portion extending between the carline and the purlins and a locking block riveted to said purlins and having a portion extending beneath said carlines to maintain said carlines and purlins 65 in interlocked relation with the lowermost portions of the carlines and purlins substantially coincident.

4. In a car roof, carline members composed of I-beams having T-shaped openings 70 in the webs thereof, in combination with T-shaped purlin members passing through the openings in said carlines with the flanges of the purlins uppermost to form supports for roofing sheets and with the flanges of the 75 purlins resting on the webs of the carlines, the webs of said purlins being notched to inclose the lower flanges of said carlines in such manner that the lower flanges of the carlines and the lower edges of the webs of the purlins are substantially coincident, a locking block riveted to one of said members and in engagement with the other of said members to maintain the upper flanges of the carlines above and spaced apart from the upper flanges of the purlins, said members being flexibly secured together by said 80 locking block.

In witness whereof I have hereunto set my hand in the presence of two witnesses.

PAUL BATEMAN.

Witnesses:

OSCAR HOCHBERG,
RODNEY BEDELL.
